CLAIM

The ornamental design for a display screen or portion thereof with graphical user interface as shown and described.

DESCRIPTION

The patent file contains at least one drawing executed in color. Copies of this patent with color drawings will be provided by the Office upon request and payment of the necessary fee.

FIG. 1 is a view of a first embodiment of a display screen or a portion thereof with graphical user interface showing the new design.

FIG. 2 is an enlarged view of the portion enclosed by the long dash-short dash broken lines in FIG. 1.

FIG. 3 is a view of a second embodiment of a display screen or a portion thereof with graphical user interface showing the new design; and,

FIG. 4 is an enlarged view of the portion enclosed by the long dash-short dash broken lines in FIG. 3.

The outer broken lines showing a portion of the display screen form no part of the claimed design. The long dash-short dash line enclosing enlargement portions of the design forms no part of the claimed design. The remaining broken lines in the drawings are for the purpose of illustrating portions of the graphical user interface and form no part of the claimed design.
